Primary Examiner — Marissa J. Cash*Assistant Examiner* — Elisheva Goldsmith*(74) Attorney, Agent, or Firm* — Michael Bartholomew(57) **CLAIM**

The ornamental design for a throwing dart toy, as shown and described.

DESCRIPTION

FIG. 1 is a bottom, front, right side perspective view of a throwing dart toy, showing my new design; FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings depict portions of the throwing dart toy that form no part of the claimed design.
